UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 19,820, dated May 6, 1890.

Application filed April 11, 1890. Serial No. 347,545. Term of patent 3½ years.

To all whom it may concern:

Be it known that I, JAMES L. FOLSOM, a citizen of the United States, residing at Brooklyn, county of Kings, State of New York, have 5 invented a new and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design is composed of a body A and a border B.

The body A is made up of clusters of leaf and flower forms. Some of these clusters are 20 composed of leaf forms, and the parts of the leaves about the centers of the clusters are rounded, so as to present somewhat the appearance of flower forms. Other clusters contain gem-shaped flower forms and various 25 leaf forms.

The border B contains clusters of flower

and leaf forms. One of these clusters in each repeat of the design is made up of leaf forms, and the parts of the leaves about the center of the cluster are rounded, so as to present 30 somewhat the appearance of flower forms. Another cluster in each repeat contains gem-shaped flower forms and various leaf forms. The outer part of the border B is composed of an undulating stem having scroll-shaped 35 branches at more or less regular intervals. The inner margin is composed of conventionalized flower forms. The outer margin contains several flower forms.

What I claim as new, and desire to secure 40 by Letters Patent, is—

1. The design for a carpet, consisting of the body A, substantially as shown.
2. The design for a carpet, consisting of the border B, substantially as shown.
3. The design for a carpet, consisting of the body A and the border B, substantially as shown.

JAS. L. FOLSOM.
